A. OLSON

BARREL SUPPORT

Filed Dec. 26, 1923

Inventor
Alfred OLSON,

Attorney

UNITED STATES PATENT OFFICE.

ALFRED OLSON, OF CLARK, SOUTH DAKOTA.

BARREL SUPPORT.

Application filed December 26, 1923. Serial No. 682,774.

To all whom it may concern:

Be it known that I, ALFRED OLSON, citizen of the United States, residing at Clark, in the county of Clark and State of South Dakota, have invented certain new and useful Improvements in Barrel Supports, of which the following is a specification.

The present invention relates to improvements in the construction of stands for barrels and has for its object to produce a device of this character which is of an extremely cheap, simple, but strong and effective construction, whereby the same may be easily and quickly secured to barrels of different sizes so as to provide a support for said barrels and whereby the barrels may be readily tilted to permit of the delivery of fluid therefrom or raised to a standing position when not thus used, so that leaking 20 of the contents through the opening in the barrel for the faucet will be thus effectively prevented and also whereby said barrel may be effectively handled.

Other objects will appear as the nature of 25 the invention is better understood, and the same consists in the novel form, combination, and arrangement of parts hereinafter more fully described, shown in the accompanying drawing, and claimed.

In the drawing, wherein like reference 30 characters indicate corresponding parts throughout the several views:

Figure 1 is a side elevation illustrating 35 the improvement applied to a barrel and supporting the latter in a substantially horizontal tilted position.

Figure 2 is a top plan view of the improvement,

Figure 3 is a front end elevation of the 40 device shown in Figure 1 with the barrel in place.

Figure 4 is an enlarged fragmentary perspective view showing the outer end portion of one of the inner arm sections, and

Figure 5 is an enlarged perspective view 45 showing one of the outer arm sections.

The stand or barrel support is preferably 50 constructed of metal and comprises a transverse cradle member 5 that is supported at the required elevation by means of a pair of side uprights 6 which are rigidly connected at their lower ends by a transverse connecting member 7. The uprights 6 and the connecting member 7 are preferably formed of 55 a single piece of strap iron, with their free end portions extended inwardly from the

upper ends of the uprights 6 to form the transverse cradle member 5, the ends of these end portions being rigidly secured together as indicated at 8.

A longitudinal rod centrally intersects 60 the cradle member 5 and is rigidly secured to the latter by the fastening means as at 8, so as to extend alongside the barrel when the latter is disposed within the cradle member as shown in Figures 1, 2, and 3. This rod is composed of forwardly and rearwardly projecting arms that are adjustable in length and the outer ends of which are provided with inwardly extending hooks 9 65 adapted to engage with the chines at the opposite ends of the barrel 10. The forwardly extending arm of the rod is longer than the rearwardly extending arm thereof, so that the uprights 6 and cradle member 70 5 may be positioned nearer the bottom of the barrel 10 than the top thereof, or to one side of the transverse center of the barrel as shown in Figure 1, when the hooks 9 are 75 engaged with the barrel chines. This rod 80 comprises an inner forward arm section 11, and an inner rear arm section 12, in the ends of which are longitudinally slidably disposed the outer arm sections 13 and 14 85 upon the outer ends of which the hooks 9 are formed. Thus, the arms of the longitudinal rod are adjustable in length, and in order to maintain the outer arms sections 13 and 14 in any adjusted position, the outer ends of the inner arm sections 11 and 12 90 are longitudinally slotted as at 15 and provided with pairs of ears as at 16 for reception of clamping bolts 17 by means of which the outer ends of the arms 11 and 12 may be 95 tightly drawn together about the inner ends of the outer arm sections 13 and 14.

As shown more clearly in Figure 3, the transverse cradle member 5 is not of true semi-circular form but is of substantially semi-oval or elliptical form so that barrels 100 of differing diameters may be disposed thereon and properly centered between the uprights 6. It is thus apparent that the device is formed in a simple and practical manner for accommodating barrels of differing heights or lengths and of differing 105 diameter.

Inclined pairs of converging braces 18 are provided between the lower ends of the uprights 6 and the outer end portions of the inner arms 11 and 12 so that the longitudinal 110 rod is effectively braced to provide a rigid

construction whereby the displacement of the longitudinal arms out of proper relation to the cradle member and upright is prevented.

5 By reason of the fact that the uprights 6 and cradle member 5 are positioned to one side of the transverse axis or center of the barrel, the remaining of the latter in its tilted position under the influence of gravity 10 is insured, and in order to sustain the barrel in a substantially horizontal tilted position against further tilting movement, a folding leg 19 is provided on the adjustable outer arm section 13 of the longer arm of 15 the longitudinal rod, the leg 19 having its upper end pivoted as at 20 to the arm section 13 so that said leg may be folded parallel with the arm section 13 when not in use.

20 From the above, it will be seen that the side edges of the transverse member 7 which connects the lower ends of the uprights 6 provides fulcrums whereby the barrel may be readily tilted to a substantially horizontal position, in which it is sustained by the action of gravity, and the engagement of the lower end of the leg 19 upon the floor or other support.

From the above description, it is believed 30 that the construction and operation as well as the advantages of the present invention will be readily understood and appreciated by those skilled in the art.

What I claim as new is:

35 1. A barrel stand including a pair of uprights, a transverse member rigidly connecting the uprights at their lower ends, a transverse cradle member carried by the upper ends of the uprights and adapted for supporting reception of a barrel, a longitudinal rod centrally intersecting the cradle and rigid with the latter, said longitudinal rod comprising forward and rear arms adjustable in length, and provided upon their 40 outer ends with inwardly extending hooks 45 designed to engage with the chines at the opposite ends of the barrel, means to maintain the arms of the longitudinal rod at any

adjusted length whereby the hooks may be maintained in engagement with barrels of different sizes, the forward arm of the longitudinal rod being of greater length than the rear arm thereof whereby the cradle member is positioned to one side of the transverse axis of the barrel when the hooks are engaged with the chines of the latter, and a folding leg carried by the longer forward arm of the longitudinal rod to sustain the barrel in a horizontal tilted position. 50 55 60

2. A barrel stand including a pair of uprights; a transverse member rigidly connecting the uprights at their lower ends, a transverse cradle member carried by the upper ends of the uprights and adapted for supporting reception of a barrel, a longitudinal rod centrally intersecting the cradle and rigid with the latter, said longitudinal rod comprising forward and rear arms adjustable in length and provided upon their outer 70 ends with inwardly extending hooks adapted to engage with the chines at the opposite ends of the barrel, means to maintain the arms of the longitudinal rod at any adjusted length whereby the hooks may be maintained in engagement with barrels of different sizes, the forward arm of the longitudinal rod being of greater length than the rear arm thereof whereby the cradle member is positioned to one side of the transverse axis of the barrel when the hooks are 75 80 85 90 95 engaged with the chines of the latter, a folding leg carried by the longer forward arm of the longitudinal rod to sustain the barrel in a horizontal tilted position, said transverse cradle member being rigid with the upper ends of the uprights so as to bodily move with the barrel together with the uprights and transverse member which connects the lower ends of the uprights when the barrel is tilted about a fulcrum defined by said transverse upright connecting member.

In testimony whereof I affix my signature.

ALFRED OLSON.
